UNITED STATES PATENT OFFICE.

JACK C. JANKUS, OF SCRANTON, PENNSYLVANIA, ASSIGNOR TO WOMANS INSTITUTE OF DOMESTIC ARTS & SCIENCES, INC., OF SCRANTON, PENNSYLVANIA, A CORPORATION OF DELAWARE.

DRESS OR GARMENT FORM.

Application filed June 26, 1920. Serial No. 392,124.

To all whom it may concern:

Be it known that I, JACK C. JANKUS, a citizen of the United States, residing at Scranton, in the county of Lackawanna and State 5 of Pennsylvania, have invented new and useful Improvements in Dress or Garment Forms, of which the following is a specification.

This invention relates to dress or garment 10 forms and the objects are to provide a form which shall be inexpensive of manufacture, light in weight, which may be packed into a relatively small space, thereby facilitating storage and shipping, and which shall be 15 readily detachable in all of its parts so that it may be easily handled with a view to facilitating and rendering less arduous the operations of fitting garments thereon.

With the above and other objects in view, 20 my invention consists of certain features of structure, combination and relation which will be more fully set forth hereinafter.

I have illustrated one embodiment of my 25 invention in the accompanying drawings, wherein:

Figure 1 is a front elevation of my improved form.

Figure 2 is a vertical section through a 30 portion of my improved form and standard.

Figure 3 is a perspective view of my improved form assembled for packing.

Figure 4 is a front elevation of a modified form of one of the bust sections.

Figure 5 is a rear elevation of the modified form illustrated in Figure 4.

Figure 6 is a cross-section through a pair of the sections showing the side flanges.

Figure 7 is a view similar to Figure 6 showing the flanges trimmed off in finished 40 form.

Referring to the drawings, in its completed condition a dress form constructed according to my invention consists primarily of two parts, the upper or bust portion 1 and the lower or skirt portion 2 which are, in practice, readily detachable, one from the other. In order to facilitate and cheapen the manufacture of this article, I prefer to make the form of papier-mâché or paper pulp and to construct each detachable section of the form in two parts, by means of an apparatus such as is described and claimed in my co-pending application Serial No. 391,873, filed June 26, 1920, and whereby the sections are

each made in two parts and are stamped 55 or compressed from paper pulp papier-mâché, in which operation they are provided with side flange portions, as at 3 and 3^a, (Figures 6 and 7) and may be provided with center line body grooves, as at 4, as indicated 60 in the modified form illustrated in Figures 4 and 5 of the drawing. When the two-part sections have been formed, they may be joined together at the side flanges by any suitable means, such as by the use of an adhesive, and the flanged portions trimmed off to give the sections of the form a neat and pleasing appearance.

In the modified form illustrated in Figure 4 the center line body grooves 4 are 70 adapted to facilitate the fitting of garments to the form as the garment may be readily centered on the form, and for this purpose the grooves bear a certain definite relation to the side flange portions which may also be 75 used for a similar purpose. It is preferred, at this time, to position the center line body grooves so that each section part will thereby be divided into two equal sections and by the provision of the side flanges and the relation existing between the center line 80 grooves and the side flanges four fixed and readily discernible guides are provided for the positioning of the garment on the form. It is preferred to provide these four indicating lines with a view to having means for the fitting of the different styles of garments, it being well known that certain garments are provided with closures at the center line of the body, others being adapted to close at 85 the side and a form constructed in accordance with my invention will automatically indicate the proper and true line along which such closure should lie and will also facilitate the proper positioning and distancing 90 of the various seams of the garment. It is further within the contemplation of this invention that the front and back center line body grooves may be filled with an insert of 95 felt or other material whereby portions of the garment may be pinned thereto and that the form sections may be covered with jersey cloth or other equivalent material, if desired, no special claim being made to this 100 feature.

Referring to the preferred form of my invention, illustrated in Figures 1 to 3 of the drawings, in order to effectively secure the

bust portion of the form upon the skirt portion the bust portion is provided at its lower part with an annular flange or collar 5. This flange or collar is made of any 5 suitable material and in some cases may be cast integral with the portion from which it depends.

The skirt portion 2 is closed at its upper 10 end by means of a spider or disk 6 which provides a seat for the depending flange of the bust portion. This spider is formed with an axial recess 7 which is adapted to receive the adjusting rod 8 of the form standard. This adjusting rod may be of 15 any suitable size or shape and is freely slideable and telescopes upon the standard rod 9. The adjusting rod may be secured at any 20 desired height by means of a set screw such as is illustrated at 10 or other suitable fastening device. The standard rod is screw-threaded into a base portion 11.

In order to facilitate storing and shipping 25 of the various units of the dress form they are so proportioned that, as illustrated in Figure 3 of the drawing, the bust form may be inserted in the lower part of the skirt form, the standard rod 9 detached from the 30 base and the adjusting rod telescoped thereon, whereupon the units may be assembled in the form indicated in the figure of drawing referred to and thereby occupying a relatively small space.

It is apparent from the foregoing description 35 that the device may be used either as a waist or skirt form or as a combination of the two, in the first use, the bust form being detached from the skirt form, in which position it is adapted to be placed in the lap of the person working thereon or on a table, 40 chair or any other convenient location, thereby rendering the fitting of the garments thereto much easier for the operator. It is also apparent that the same operation may 45 be conducted with the skirt form when only that portion is to be used.

I claim:—

1. In a dress form, the combination of a bust member having an annular flange projecting from the lower part thereof, a skirt form, and a supporting standard, said skirt 50 form having a member secured thereto adjacent its upper edge, said member providing a seat for the annular flange and being provided with an axial recess for receiving one end of said supporting standard. 55

2. In a dress form, the combination of a bust portion formed with an annular flange at the lower end thereof, a skirt portion, a member secured to the skirt portion near its upper end providing a seat for said annular flange, the lower part of said skirt portion being open and of such size as to permit the bust portion to be placed therein, a standard detachably engaging said member for supporting said skirt form, and a second 60 standard telescoping within said first named standard, whereby said bust and skirt portions and standards can be readily disassembled and placed in compact form by inserting the bust within the skirt portion and 65 arranging the standards in telescoping relation.

3. In a dress form, the combination of a bust portion provided with an annular flange at its lower end, a skirt portion, a 70 disk attached to the upper end of said skirt portion providing a seat for said annular flange, said disk having an axial circular recess formed therein, a supporting standard having a shaft formed with a cylindrical 75 portion adapted to engage in said recess for rotatably supporting the bust and skirt portions.

In testimony whereof I have hereunto set my hand in presence of two subscribing 85 witnesses.

JACK C. JANKUS.
